(57) **CLAIM**

The ornamental design for a sensor for industrial robot, as shown and described.

DESCRIPTION

FIG. 1 is a top, front, and right side perspective view of a sensor for industrial robot showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the sensor for industrial robot that form no part of the claimed design. The dot-dashed broken lines shown in the figures illustrate the bounds of the claim and form no part thereof.
